UNITED STATES PATENT OFFICE

2,061,861

PROCESS FOR THE PRODUCTION OF IRON SLEEPERS

Carl Wallmann, Julius Grossweischede, and Bernhard Kruse, Mulheim-Ruhr, Germany, assignors to the firm Vereinigte Stahlwerke Aktiengesellschaft, Dusseldorf, Germany

Application August 15, 1933, Serial No. 685,250
In Germany August 24, 1932

2 Claims. (Cl. 29—169)

This invention relates to an improvement in or modification of the invention described and claimed in our prior patent application Serial No. 589,466 issued December 10, 1935, as Patent No. 2,023,827.

The said prior application relates to a method of producing iron sleepers having ribbed plates or ribbed reinforcements for engaging the rails in which a flat iron, the thickness of which corresponds approximately to the thickness of the rib, or a rolled iron with a continuous central reinforcement, having also the thickness of the rib, are pressed in a die into the form of a sleeper, the ribs being formed in known manner by pressing down or forging the surplus material.

The object of the present invention is to improve this method by reducing the power required for the pressing process. According to the present invention, this is obtained by providing the preliminarily worked piece while still in the flat condition with ribs for engaging the rails, and then pressing it into the final trough-like shape.

Preferably the preliminary work piece is in the first pressing step at the same time widened to a certain degree so that its width corresponds approximately to that of the developed sleeper profile.

A further feature of the present invention is that the transverse section of the sleeper in the centre, that is between the rib projections, either in its entirety or in part, may vary and width, height or thickness may have different dimensions from those of the standard sleeper. The aim and result of this is also to reduce, as much as possible, the power required for the pressing.

In order that the invention may be more clearly understood one particular form thereof will now be described with reference to the accompanying drawing wherein:

Figure 1 is a side view of a preliminary work piece,

Figure 2 is a plan view according to Fig. 1,

Figure 3 is a cross section through line *a*—*b* of Fig. 2.

Figure 4 is a side view of a preliminary work piece after the first pressing,

Figure 5 is a plan view according to Fig. 4,

Figure 6 is a cross section on line *a*—*b* of Fig. 4,

Figure 7 is a cross section on line *c*—*d* of Fig. 4,

Figure 8 is a longitudinal section of a finished sleeper after the second pressing,

Figure 9 is a plan view of Fig. 8,

Fig. 10 is a cross section on line *a*—*b* of Fig. 8,
Figure 11 is a cross section on line *c*—*d* of Fig. 8.

Referring to the drawing the flat preliminary work piece having a continuous longitudinal rib 5 or reinforcement 1, as shown in Figures 1 to 3, is first pressed into the shape shown in Figures 4 to 7 in which the longitudinal rib 1 is partially pressed down except at its middle portion and at the rail contact parts in such a manner that 10 a flat intermediate work piece is produced which has a longitudinal rib 4 in its middle portion and two rail engaging projections 2 at each rail contact part. During this pressing operation the work piece which remains flat is widened to such 15 a degree, for example 20—25%, that its width corresponds to that of the developed shape of the final sleeper; the middle portion which is provided with the longitudinal rib 4 remains smaller in width than the other parts. The final sleeper 20 thereupon is produced by pressing the said intermediate piece into the desired trough-like shape 3, according to Figs. 8 to 11, during which operation the dimensions of the work piece are not changed so that the final sleeper 25 is provided with a longitudinal rib 4' at its middle portion between the rail contact parts and with the rail engaging projections 2' corresponding to that of the intermediate work piece of Figs. 4 to 7; further the final sleeper has likewise a 30 lesser width in its middle portion than at the other parts.

The present invention, however, is not limited to this particular example. In particular the fundamental idea of shaping the ribs first, while 35 the working piece is still in its flat condition, can be advantageously effected by means of a rolling mill. The particular shape here shown for the preliminary work piece is also not of 40 essential importance.

What we claim and desire to secure by Letters Patent in the United States is:

1. Process for the production of iron sleepers consisting in partially pressing down the longitudinal rib of a flat preliminary work piece except at its middle portion and the rail contact parts in such a manner that a flat intermediate work piece of a width corresponding to that of the developed shape of the final sleeper is produced which has a longitudinal rib in its middle 50 portion and at least two rail engaging projections 45 at each rail contact part, the said intermediate piece having a lesser width at its middle portion than at the other parts, and then pressing the said intermediate piece without changing its 55

dimensions into the trough-like shape of the final sleeper.

2. Process for the production of iron sleepers consisting in pressing down the longitudinal rib of a flat preliminary work piece except at the rail contact parts in such a manner that a flat intermediate work piece of a width corresponding to that of the developed shape of the final

sleeper is produced which has two rail engaging projections at each rail contact part and then pressing the said intermediate piece without changing its dimensions into the troughlike shape of the final sleeper.
